UNITED STATES PATENT OFFICE.

ALFRED W. F. GUEST, OF BROOKLYN, NEW YORK, ASSIGNOR TO MERGENTHALER LINOTYPE COMPANY, A CORPORATION OF NEW YORK.

TYPOGRAPHICAL MACHINE.

1,116,416.

Specification of Letters Patent. Patented Nov. 10, 1914.

Application filed April 7, 1914. Serial No. 830,116.

To all whom it may concern:

Be it known that I, ALFRED W. F. GUEST, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such for instance as line casting machines wherein circulating matrices are assembled in a line and presented to a mold, and then elevated and passed through a distributing mechanism by which they are returned to the magazine channels from 15 which they were originally released.

More particularly, it relates to the distributing mechanism, such as shown for instance in Letters Patent of the United 20 States No. 436,532, to O. Mergenthaler, wherein the toothed matrices are lifted successively to and suspended from a grooved distributor bar, along which they are carried by the threads of adjacent screws and 25 delivered to their proper channels.

As these machines are commonly constructed, a matrix is lifted into engagement with the feed screws at each rotation of the 30 latter, or in other words, there is a matrix between each turn of the thread and the turn next thereto. When thick matrices are delivered in these adjacent positions, the space between them is small, and it sometimes occurs 35 that a falling matrix will be overtaken by the next one before it clears the bar. This results not only in an interference with the proper distribution but also in injury to the matrices.

40 The object of my invention is to overcome this trouble by providing between the matrices a space sufficient to permit the free descent of the first one without conflict with a following one. Several mechanisms 45 have been previously devised to effect this result, as for instance that presented in U. S. Letters Patent No. 942,848 to F. B. Converse, wherein is employed a matrix lifting finger and means to hold it momentarily 50 out of engagement with a second matrix, these means being controlled by the thickness of the individual matrices.

In the use of the Converse mechanism, as

specifically embodied, the ordinary matrices are delivered consecutively between adjacent turns of the screw thread, while thicker matrices are delivered between alternate turns with a space between them, or in other words, the ordinary matrices are located in the first, second, third, etc. spaces, 60 while the thicker matrices would be located in the first, third, fifth, etc. spaces. This arrangement is entirely satisfactory for general use, but becomes inadequate in connection with much thicker matrices, such as 65 those of the "display" variety. I therefore propose to employ means for the delivery of such extended matrices with even greater intervals between them, and to that end I have shown my invention as preferably 70 adapted to the Converse mechanism, but with certain added means for holding the lifting finger out of engagement with a second matrix during a plurality of its operations, instead of during a single operation 75 only.

In the accompanying drawings, I have shown my invention in preferred form and by way of example, and as applied to the specific kind of devices referred to, but obviously many changes and variations may be made therein, and in its mode of adaptation, which will still be comprised within its spirit. Similarly, it may be applied to other forms of typographical machines, 80 such as typesetters, typecasters, and the like, which handle type or dies, instead of matrices. Generally speaking, I desire it to be understood that I do not limit myself to any specific form or embodiment, except 85 in so far as such limitations are specified in the claims.

In the accompanying drawings: Figure 1 is a rear view of a portion of the distributing mechanism, etc., with my improvements 90 embodied therein; Figs. 2, 3 and 4 are somewhat similar views, showing the parts in different positions; Fig. 5 is a section on the line 5—5 of Fig. 4; Fig. 6 is a detail of the first and second elevators in coöperative 95 relation; Fig. 7 is a perspective of the specific matrix employed; and Fig. 8 is a bottom view thereof.

As is usual in machines of this class, the matrices X are lifted from the casting position by the first elevator A and thence trans-

ferred to the second elevator B (see Fig. 6), at which time the toothed combinations X¹ of the matrices are brought into engagement with the grooved bar of the second elevator. 5 The elevator B then rises to the position shown in Fig. 1, when the matrices are shifted therefrom into the distributor box C by the transfer device D. They are then elevated by the reciprocating finger E into 10 operative relation to the distributor rail F and screws G, by which they are restored to their proper channels in the magazine. The parts so far described are or may be of the usual or any desired construction, and in 15 themselves constitute no part of my invention, except as hereinafter specified.

The lifting finger E is normally spring-pressed toward the advancing line so as to engage and elevate the leading matrix there- 20 of, the parts being so timed that when the usual or ordinary matrices are employed they will be raised into engagement with the consecutive turns of the screws G. The finger E is provided with a hook H, so that 25 when the finger is moved laterally by a matrix of more than normal thickness, the hook will engage the fixed element J, thereby holding the finger out of operative position when it is next reciprocated, and there- 30 by establishing an interval of one thread space between the thick matrix and the one following it on the distributor rail. These parts are substantially the same in construc- 35 tion and mode of operation as the similar ones disclosed in the Converse patent, but the interval thus provided is insufficient to accommodate the considerably greater thickness of "display" matrices and the like. I therefore employ additional means whereby 40 the lifting finger is held out of operative position during a plurality of reciprocations, as distinguished from a single reciprocation as in the mode of operation just described. In the specific form illustrated, 45 the interval thus secured for the thick display matrix is two thread spaces instead of one, although it will be subsequently obvious that it may be increased to any extent desired. 50 To obtain the continued inoperative position of the finger E, I preferably rely upon the peculiar construction of the matrix X, which to that end is formed on its bottom side with the transverse notch X², adapted 55 to engage the upper end of the finger E, as the matrix is advanced by the screws G.

The operation of my improved devices will now be obvious. As previously stated, when ordinary matrices are employed they 60 are delivered to successive thread spaces, and the thicker matrices to alternate thread spaces. However, when the still thicker or "display" matrix X is presented at the end of a line, it is engaged at its forward lower 65 corner by the finger E, as shown in Fig. 1.

The matrix is then lifted into operative relation to the bar F and screws G, and the lateral movement of the matrix tilts the finger to the left, and when it descends its hook H engages with the element J, as 70 shown in Fig. 2. The finger E then rises a second time and its end enters the notch X² of the matrix, as shown in Fig. 3. The continued lateral movement of the matrix again shifts the finger E to the left, and when it descends its hook H engages the element J 75 a second time, as shown in Fig. 4. In other words, the finger has been held out of operation during two successive reciprocations. The matrix has by this time practically 80 cleared the finger E, so that when it rises and descends a third time it is allowed to return to normal position, as shown by dotted lines in Fig. 4. In this manner I effect an interval of a plurality of spaces 85 between the matrices, instead of none, or a single one, as has been the case before. That is to say, a matrix of ordinary thickness permits the regular operation of the lifting devices; a matrix of greater thickness 90 renders it inactive during one operation; and a still thicker matrix renders it inactive during a plurality of operations. Obviously the same principle may be extended, according to the thickness of the matrix and the 95 necessities of the situation, and very simply by forming additional notches X² in the matrix, as the thickness increases.

As before stated, I have shown my invention only in preferred form and by way of example, and as applied to a particular type of mechanism, but obviously many modifications and alterations therein, and in its mode of application, will suggest themselves to those skilled in the art, without departure 105 from its scope.

Having thus described my invention, its construction and mode of operation, what I claim and desire to secure by Letters Patent of the United States, is as follows:

1. In a mechanism of the class described, the combination of a matrix lifting finger, and automatic means for holding it out of engagement with a second matrix during a plurality of its operations.

2. In a mechanism of the class described, the combination of a matrix lifting finger, and means for holding it out of engagement with a second matrix during a plurality of its operations, the said means being rendered active by matrices of one thickness, but not by those of another thickness.

3. In a mechanism of the class described, the combination of a matrix lifting finger arranged to yield before the matrix being elevated, means to keep the finger momentarily out of action when it yields beyond a certain point, and means whereby the matrix will cause the finger to yield to such point a plurality of times; whereby a plu- 130

rality of idle strokes of the finger is secured when matrices of a given thickness are elevated.

4. In a mechanism of the class described, 5 the combination of a distributor feed screw, devices for delivering the individual matrices thereto, and automatic means for holding said devices out of action until the screw has completed a plurality of rotations, when a matrix of a given thickness is 10 presented thereto.

5. The combination of distributing mechanism, devices for delivering matrices thereto, and automatic means to render said devices 15 inactive in their successive operations.

6. In a mechanism of the class described, comprising matrices of different thicknesses, the combination of a matrix lifting finger, and means whereby matrices of a given 20 thickness render said finger momentarily inactive, the said matrices being so formed as to render said finger momentarily inactive for a second time also, for the purpose described.

25 7. In a mechanism of the class described, the combination of a line of matrices, and a device for detaching the leading matrices from the line, the matrices of a given thick-

ness being formed to engage the said device after their detachment from the line and 30 render it momentarily inactive.

8. In a mechanism of the class described, the combination of a line of matrices, and a lifting finger to detach the leading matrices therefrom, certain matrices being each 35 formed with a notch in their bottom edges to engage the finger after their detachment from the line to render the finger momentarily inactive.

9. In a mechanism of the class described, 40 the combination of a matrix lifting finger, and means to hold the same momentarily out of action, the said means being controlled by the form of the matrices.

10. In a mechanism of the class described, 45 the combination of a matrix lifting finger, and means to hold the same momentarily out of action, the said means being controlled by both the thickness and form of 50 the matrices.

In testimony whereof I have affixed my signature in presence of two witnesses.

ALFRED W. F. GUEST.
